UNITED STATES PATENT OFFICE

2,577,659

GARBAGE INCINERATOR

Rainer H. Knipping, San Antonio, Tex.

Application October 9, 1947, Serial No. 778,819.

9 Claims. (Cl. 110—15)

1

The present invention relates to an apparatus for disposing of garbage and the like.

The primary object of the invention is to provide a garbage incinerator which will accommodate so-called "free" garbage in the condition as collected, without any preliminary processing, separating, or classifying of component parts thereof.

A further object of the invention is to provide an apparatus which will burn all combustible materials, and which will accommodate large and small non-combustible objects, such as tin cans, boxes, bottles and the like, and which will separate the non-combustibles from the ash, at the conclusion of the burning operation.

Another important object is to provide means for dehydrating the garbage, prior to the burning thereof, to facilitate the burning and to make the combustion more efficient. To this end, the invention provides an arrangement wherein the heated products of combustion are conducted, by countercurrent flow directly into contact and intermingled with and pass through the incoming garbage, so as to extract the moisture therefrom, whereby substantially completely dehydrated material is delivered to the combustion zone.

A further object of the invention is to provide an improved infeed system, in which the garbage is preheated, prior to the delivery of the same to the drying zone.

Another important object of the invention is to provide a combustion zone, where the dry material is burned, in which the material is continuously and slowly moved along a predetermined path as the burning takes place, with substantially continuous discharge of the ash and non-combustibles therefrom.

Another object is to provide improved separating means, in combination with the traveling bed of combustible material, to separate the non-combustible objects from the ash.

A further object is to provide means for delivering preheated air under pressure to the combustion chamber at a plurality of points, to promote the most efficient combustion of the material.

Another object of the invention is to provide improved draft controlling instrumentalities, whereby the pressure and temperature conditions throughout all portions of the apparatus may be controlled at will.

Other and further objects and advantages of the invention will be apparent from a consideration of the following description of an illustrative embodiment, shown in the accompanying drawings, in which,

Figure 1 is a vertical section and partial elevation of an apparatus constructed in accordance with the invention;

Figure 2 is a transverse section and partial elevation, taken substantially on line 2—2 of Figure 1;

2

Figure 3 is an enlarged vertical section of the discharge end of the combustion chamber;

Figure 4 is an enlarged vertical section of the discharge end of the rotary drier and associated parts;

Figure 5 is a similar section adjacent the upper end of the rotary drier, and

Figures 6 and 7 are side and front elevational views of a control panel.

The apparatus shown for purposes of illustration in the accompanying drawings is relatively large and massive, and is of a size to dispose of the garbage collected by cities and towns, although it should be understood that certain features of the invention may be employed in smaller installations. A plurality of pairs of upwardly extending frame members 10, 11, 12, 13 and 14 support lower and upper platforms 15 and 16, to which access may be gained by suitable stairways 17 or ladders or the like. Above the upper platform 16, there is an elongated, inclined, cylindrical, rotary drier, represented generally at 20 and comprising a metallic outer shell 21, a refractory lining 22 and a pair of annular tracks 23, 24, supported by rollers 25 journaled on supports carried by the platform, as is well understood in the rotary kiln art, the drier being driven by suitable means, such as an electric motor and speed reducer 26 having a pinion 27 in mesh with a large annular spur gear 28, encircling the shell.

At the upper end of the drier, there is a large hopper 30 having a discharge throat 31 communicating with the interior of the drier and supported by appropriate frame members 32 positioned on the upper platform 16. A removable access and inspection door 33 closes an opening in the hopper adjacent the discharge throat, above a walkway 35, carried by the framework.

The upper end of the hopper 30 carries a cover 36, which is connected to a forwardly extending hood 37, constituting the top of a housing including side walls 38 and bottom wall 39 for an infeed conveyor 40. The latter is constituted by an endless belt or the like 41 having a plurality of wings or flights 42 projecting perpendicularly from its surface, the belt being trained about rollers 43, and 44 at the entrance and discharge ends respectively, and being supported by a bed including longitudinally extending frame members 45, carried by transverse beams 46, secured at their ends to the pairs of vertical posts. Either roller may be positively driven, to impart movement to the conveyor. As indicated in Figure 4, a chute 47, which may constitute the bottom of a hopper, may be positioned to deliver the garbage to the upper run of the conveyor.

An elevated platform 50, at the left or rear end of the apparatus, is supported upon the upper ends of the vertical frame members 11 and similar frame members 51, extending upwardly from the upper platform 16. Mounted on the platform 50 is a motor driven suction fan housing 52, com-

municating at its upper end with a discharge stack 53 and at its lower end with an intake chamber 54. The latter is connected by laterally, downwardly and inwardly extending conduits 55 and 56 (Figure 2) to a junction box 57, disposed above the upper end of the rotary drier and below the discharge end of the conveyor 40, and suspended from the floor 39 of the conveyor housing. The conduits 55 and 56 extend laterally around the conveyor housing and enter the box 57 through the sides thereof.

Referring to Figures 1 and 5, the upper surface of the hopper throat 31 is provided with a flange opening 58, to which is connected a flue pipe 59, adapted to lead gases flowing through the rotary drier to the rear end wall of the junction box 57, for flow through conduits 55 and 56 to the fan housing 52 and stack 53.

The right-hand end wall of box 57 is in communication through an opening 60, controlled by a damper 61, with a forwardly extending bypass conduit 62, positioned above the drier 20 and below the conveyor 40, and communicating at its other end with the combustion chamber, now to be described.

Supported upon the lower platform 15 is a combustion chamber made up in part of refractory brickwork or the like and comprising vertical side walls 65, a front end wall 66, terminating upwardly in a forwardly curved hood 67, embracing the lower end of the drier and the lower end of the by-pass conduit 62, and a rear top wall 68, terminating at its rear end in a downwardly extending end wall 69. It will be understood that the top wall 68 is maintained at a relatively high temperature by the combustion in the chamber therebelow.

A traveling grate 70, of known construction is trained for movement about rolls 71 and 72, mounted on shafts supported in any appropriate manner, preferably in external bearings carried by the platform 15, movement being imparted to the grate by slowly driving one or the other of the rollers, to advance the bed of burning material, indicated at 73, toward the left in Figures 1 and 3.

Above the top wall 68 of the combustion chamber is a housing 75 for a two-stage power blower 76, adapted to supply air to the combustion chamber. The intake of the blower housing is connected to a screened suction chamber 77, positioned in the space between the furnace top wall 68 and the lower end of the drier 20, whereby air, heated by said top wall and by the lower end of the drier, is drawn into the blower and delivered to the combustion chamber. The discharge end of the blower 75 is connected by a downwardly extending conduit 78 to a wind box 81 having a centrally located, forwardly projecting outlet 79, controlled by an adjustable damper 80, and laterally and forwardly extending passages 82, at the lower end thereof, leading to the space 83, below the traveling grate. A plurality of laterally, upwardly and inwardly extending conduits 85 deliver air from this substantially confined space, below the grates, to tuyères 86 in the side walls 65 of the combustion chamber, above the traveling grate.

Extending through the wind box 81 and the forwardly projecting, damper controlled opening 79 is a pipe 87 having a burner nozzle 88 on the inner end thereof, for the delivery of fuel oil or gas to the combustion chamber for initiating the combustion of the garbage, as hereinafter explained.

At the discharge end of the chain grate 70, the combustion chamber end and side walls are shaped to provide a hopper 90, having a throat 91, delivering the burned material and non-combustibles to a double screen shaking grate 92 extending transversely of the combustion chamber and adapted to sift ashes downwardly, but to deliver unburned objects, such as cans, bottles and the like to one side, as indicated by the arrow in Figure 2. In a casing 93, below the shaking screen 92, there is positioned an ash conveyor 94, arranged to deliver the ash transversely, in the opposite direction. Take-off conveyors, not shown, may receive the ash and non-combustible objects, or suitable receptacles may be employed for this purpose.

The front wall 66 of the combustion chamber has an opening 100, supporting an outwardly extending conduit 101, having an adjustable damper 102 in its outer end, communicating with external atmosphere, so that cool air in variable amounts may be drawn into the lower end of the rotary drier 20, to control the temperature thereof.

It should be understood that the fans and blowers in the housings 52 and 75 are driven by variable speed electric motors and that the speed of rotation of the rotary drier and the speed of movement of the traveling grate can also be varied at will. Similarly, the dampers 61 and 102 are variable. As a result, the air pressure and temperature conditions at all points in the apparatus may be controlled at all times.

In order that proper control of the pressure and temperature conditions in the apparatus may be effected, instruments are provided for continuously reading and recording these conditions. Electrical temperature taking devices, such as thermocouples are positioned within the apparatus as indicated at 105, 106, 107, and 108. Air pressure responsive devices are positioned at 110 and 111, while draft or sub-atmospheric pressure responsive devices are inserted as indicated at 112, 113, 114, and 115. All of these devices are preferably connected to actuate external registering or indicating devices.

Referring to Figure 7 showing the control panel, the four temperatures taken by the thermocouples 105, 106, 107, and 108 may be read on the indicator and recorder 120. Toggle switch manipulating handles 121 and 122 may be shifted to close and open the damper 102, to control the admission of cooling air to the lower end of the rotary drier, when the temperature conditions indicate that a change is desired.

Frame 123 encloses indicators for the several air pressure and draft pressure devices. Thus, the air pressure in the wind box 78, determined by device 111 indicated at 111', the furnace draft at point 105, indicated by gage 105', the furnace uptake draft at 106 by gage 106', the by-pass draft at point 107 by gage 107', and the stack draft at point 108 by gage 108'.

Controller 125 may be employed to control the speed of the stack exhaust fan in casing 52, while controller 126 may be connected to control the speed of the furnace force draft blower 75. These controllers may be automatic or manual.

The device indicated at 127 may indicate and record the speed of movement of the infeed conveyor 40 in feet per minute and may have associated therewith controlling devices 128, 129, 75 to decrease or increase the speed of movement

thereof. Similarly, the speed of rotation of the rotary drier 20 may be indicated at 130 and decreased or increased by controllers 131, 132. Finally, the speed of movement of the grate 70 may be indicated at 135 and decreased or increased by controllers 136 and 137.

It is thought that the operation of the apparatus of the present invention will be clear from a consideration of the foregoing description. During normal operation, garbage, mixed with trash and non-combustibles, as collected by a city refuse department, for instance is delivered by a clam shell or any appropriate mechanism, to the conveyor 40, by dropping the same upon the hopper plate 46 (Figure 4). The conveyor moves the material at a substantially constant rate, rearwardly, toward the left, under the hood 37 and discharges the same into the hopper 30. During this movement, the material is somewhat preheated by heat rising from the drier 20 and the by-pass conduit 62. The garbage falls from the hopper 30 by gravity into the rear, entrance end of the rotary drier. It passes slowly toward the discharge end thereof, and is constantly tumbled and agitated during this passage. Hot products of combustion simultaneously flow through the drier, countercurrent to the garbage, and thereby dehydrate the same. The moisture laden products of combustion pass upwardly through conduit 108 to junction box 151 and thence, through the lateral pipes 55 and 56 to the suction fan 52 and stack 53.

The dehydrated garbage falls by gravity from the lower end of the rotating drier 22 upon the traveling grate 70, where it is moved continuously in a rearward direction toward the left, as the burning continues. Air to support this combustion is delivered by fan 15 to wind box 81, from where it flows through inlet 79, above the burning mass and, through passages 82 to the space below the grate. Some of the air delivered to this undergrate space flows upwardly through the grate and the material thereon and other portions are delivered by side passages 85 to tuyères 86, above the grate.

If the temperature in the rotary drier rises unduly, it may be lowered in two ways, i. e. by opening the damper 102, to admit atmospheric air for flow through the drier and by opening the damper 61, thereby diverting a substantial portion of the hot gases through the by-pass pipe 62, for delivery directly to the stack. By varying the speed of the fans 75 and 52 and by changing the positions of the dampers and by varying the speeds of movement of the infeed conveyor, the drier and the traveling grate, nice control of the conditions within the incinerator may be effected.

The ash and non-combustibles are separated by the screen 92 and conveyed to separate points of delivery by the screen and the ash conveyor 94, respectively.

During the normal operation of the apparatus, the garbage, burning on the traveling grate 70, supplies sufficient heat to dehydrate the incoming garbage, and the operation continues, without the addition of further fuel. However, after the apparatus has been shut down and when it is to be started up again, heat for dehydrating the incoming garbage may be supplied by the burner 88. The burner may be shut off, as soon as a substantial bed of burning garbage has been built up on the grate 70.

Although the apparatus has been described with considerable particularity in this specification, it is to be understood that the invention is

not limited to the details of construction shown in the accompanying drawings and referred to above, but includes all modifications coming within the scope of the appended claims.

5 I claim:

1. A garbage incinerator comprising an elongated, inclined, cylindrical, rotary drier, means for rotating the same, an elongated housing in superimposed, closely spaced, heat exchange relation above the drier, means within the housing for delivering material to the interior of the upper end of said drier, a stack disposed exteriorly of the housing having communication with the interior of the upper end of the drier, a combustion chamber below the lower end of the drier, in direct communication therewith for the delivery of products of combustion thereto, a grate in said chamber positioned to receive material from the drier and means for delivering air under pressure to the combustion chamber to support combustion of the material therein, the products of combustion passing through the drier serving to pre-heat the material thereabove on the material delivery means in the housing.
- 10 2. A garbage incinerator comprising an elongated, inclined, cylindrical, rotary drier, means for rotating the same, an elongated housing disposed above the drier in alignment and in heat exchange relation therewith, a conveyor within the housing for delivering material to the interior of the upper end of the drier, a stack disposed above the upper end of the drier, exteriorly of the housing, having communication with the interior of the drier adjacent the upper end thereof, a combustion chamber having direct communication with the lower end of the drier, a by-pass conduit extending from the combustion chamber to the stack and positioned between and in alignment with the housing and the drier, and means for varying the relative proportion of products of combustion passing from the combustion chamber through the drier and through the by-pass connection, respectively, to the stack.
- 15 3. A garbage incinerator comprising an elongated, inclined, cylindrical rotary drier, means for rotating the same, an elongated housing disposed above the drier in alignment and in heat exchange relation therewith, a conveyor within the housing for delivering material to the interior of the upper end of the drier, a stack positioned above the upper end of the housing and drier, a junction box between the upper end of the drier and housing, conduit means disposed exteriorly of the housing extending from the junction box to the stack, means establishing communication from the upper end of the drier to the junction box, a combustion chamber having direct communication with the lower end of the drier to receive material therefrom and to deliver products of combustion thereto and having a portion projecting above the drier, a by-pass conduit disposed between the drier and the housing and communicating from the upwardly projecting portion of the combustion chamber to the junction box, and means for varying the relative proportion of products of combustion passing through the drier and through the by-pass conduit, respectively, to the junction box and thence to the stack.
- 20 4. A garbage incinerator comprising an infeed conveyor, a hopper at the discharge end thereof having a laterally directed, inclined delivery throat, an elongated, inclined rotary drier having its upper end registering with the lower end of said throat for the reception of garbage

therefrom, a combustion chamber adjacent the lower end of the drier positioned to receive material therefrom and to deliver products of combustion thereto for flow therethrough, said throat having substantially the same diameter as the drier, to receive all of the products of combustion flowing therethrough, and having an opening in its upper surface for the escape of said products of combustion, a stack, means connecting said opening with said stack, and means for inducing a flow of said products from said opening through said connecting means to said stack, whereby the products do not flow through said hopper.

5. A garbage incinerator comprising an infeed conveyor, a hopper at the discharge end thereof having a laterally directed, inclined delivery throat, an elongated, inclined rotary drier below and in the same vertical plane as the conveyor and having its upper end registering with the lower end of said throat for the reception of garbage therefrom, a combustion chamber adjacent the lower end of the drier positioned to receive material therefrom and to deliver products of combustion to the lower end of the drier for flow therethrough into said throat, a stack above said conveyor at the upper end of the drier, conduit means extending around the conveyor and communicating with said throat in its upper surface, and a fan associated with said stack to induce said products of combustion to flow to the stack from the throat without flow through the hopper.

6. A garbage incinerator comprising an infeed conveyor, an elongated housing substantially enclosing said conveyor, a hopper at the discharge end of the conveyor having a laterally and downwardly inclined delivery throat, an elongated, inclined, rotary drier positioned below and in the same vertical plane as said housing and conveyor and having its upper end registering in substantially sealed relation with said throat for the reception of garbage therefrom, a combustion chamber adjacent the lower end of the drier positioned to receive material from the drier and to deliver products of combustion thereto for flow therethrough into said throat, a stack positioned above said housing at the discharge end of the conveyor, conduit means communicating with the stack, laterally spanning the housing and communicating with said throat through an upper portion thereof, and a fan in the stack whereby said products of combustion flow from the drier through the throat to the stack without passing through the hopper or conveyor housing.

7. A garbage incinerator comprising an infeed conveyor, an elongated housing substantially enclosing said conveyor, a hopper at the discharge end of the conveyor having a laterally and downwardly inclined delivery throat, an elongated, inclined, rotary drier positioned below said housing and conveyor and having its upper end registering in substantially sealed relation with said throat for the reception of garbage therefrom, a combustion chamber adjacent the lower end of the drier having a traveling grate therein positioned to receive material from the drier and to deliver products of combustion thereto for flow therethrough into said throat, a stack positioned above said housing at the discharge end of the conveyor in the same vertical plane as the drier and housing, conduit means communicating with the stack, laterally spanning the housing and communicating with said

throat through an upper portion thereof, and a fan associated with said stack whereby said products of combustion flow from the drier through the throat to the stack without passing through the hopper or conveyor housing.

8. A garbage incinerator comprising an infeed conveyor, an elongated housing substantially enclosing said conveyor, a hopper at the discharge end of the conveyor having a laterally and downwardly inclined delivery throat, an elongated, inclined, rotary drier positioned below said housing and conveyor and having its upper end registering in substantially sealed relation with said throat for the reception of garbage therefrom, a combustion chamber adjacent the lower end of the drier positioned to receive material from the drier and to deliver products of combustion thereto for flow therethrough into said throat, a stack positioned above said housing at the discharge end of the conveyor, an exhaust fan associated with said stack, and a pair of conduits extending laterally in opposite directions and upwardly to the stack around the outside of said housing and communicating with said throat, whereby said products of combustion are withdrawn therefrom, without entering the hopper or the conveyor housing.

9. A garbage incinerator comprising an infeed conveyor, an elongated housing substantially enclosing said conveyor, a hopper at the discharge end of the conveyor having a forwardly and downwardly inclined delivery throat, an elongated, inclined, rotary drier positioned below and in the same vertical plane as said housing and conveyor, and having its upper end registering in substantially sealed relation with said throat for the reception of garbage therefrom and for the flow to said throat of gases from the drier, a combustion chamber adjacent the lower end of the drier positioned to receive material from the drier and to deliver gaseous products of combustion thereto for flow therethrough into said throat, a stack positioned above said housing at the discharge end of the conveyor, conduit means communicating with the stack, laterally spanning the housing and communicating with the throat through the upper portion thereof below the housing, a by-pass conduit extending from the combustion chamber to the last mentioned conduit means, and means for varying the relative proportion of said gaseous products of combustion passing through the drier and through the by-pass conduit to said conduit means, whereby said products of combustion flow to the stack after passage through the drier or through the by-pass conduit without passing through the hopper or the conveyor housing.
